ROLLER FOR A PAINT ROLLER

Esther C. Watzulik, Cleveland, Ohio, assignor to The Sherwin-Williams Company, Cleveland, Ohio, a corporation of Ohio

Application January 12, 1955, Serial No. 33,955

Term of patent 14 years

(Cl. D9—2)

FIG. 2

Fig. 1 is a perspective of a roller for a paint roller embodying the ornamental design.

Fig. 2 is a development of the roller showing the full surface of the roller shown in Fig. 1.

I claim:

The ornamental design for a roller for a paint roller, substantially as shown.
